PANEL ASSEMBLY UNIT

Charles F. Sperry, Norfolk, Va., assignor to The Philip Carey Manufacturing Company, a corporation of Ohio

Application January 12, 1938, Serial No. 184,649

9 Claims. (Cl. 20—15)

This invention relates to a device for assembling boards or panels in position and particularly pertains to a unit assembly for fastening ceiling, panel, or partition boards in position in a building or similar structure. The unit comprises parts which may be readily connected and disconnected, and are adapted for use with panels of any design.

Generally described, the invention comprises a unit assembly composed of a base member that may be attached to a foundation, studding, or any frame work to which panels are to be applied. The base member is provided with a socket to receive a spring clip attached to a finishing strip, whereby the strip may be readily applied and removed without using nails, screw, or other means of attachment. The base member may also be provided with a seating portion, preferably resilient, on which the panels may be seated and supported. The base member and finishing strip, with suitable cooperating means for automatically locking together are indispensable elements of the assembly. Other means, if desired, may be employed to more securely hold the panels in place.

For a better understanding of the invention, reference may be made to the accompanying drawing, in which—

Fig. 1 is an elevational view of a section of a partition wall embodying the invention and showing different steps of assembling the unit;

Fig. 2 is a cross-sectional view on line 2—2 of Fig. 1;

Fig. 3 is a cross-sectional view on line 3—3 of Fig. 1;

Fig. 4 is a cross-sectional view on line 4—4 of Fig. 1;

Fig. 5 is a perspective view of a holding clip; and

Fig. 6 is a perspective view of the spring clip for securing the finishing panel.

Referring specifically to the drawing in which like numerals are used to designate like parts, numeral 1 designates panels or wall boards employed for finishing the walls or ceilings of a building between conventional spaced apart wooden stud or joist members 2 of a building structure. These members could be metal or other suitable material as well as wood if desired. They merely typify the frame work of any partition or wall to be paneled.

A base member 3 may be attached to each of the spaced apart studs or to those which are to support the ends of the panels, and the panels usually are of standard width to bridge and span

the space between two adjacent joists. Member 3 may be conveniently attached by bolt means 4 projected therethrough and through the stud with a clamp nut 5 screwthreaded on the end of the bolt to draw the head of the bolt against member 3. This, too, is merely representative of any suitable fastening means as it is immaterial how the member 3 is attached to the joist. The base member is formed of relatively light metal having its opposite side edges folded back at 6 to extend substantially parallel with the portion 7 for a distance and then bent in to form spaced apart terminals 8 to provide a socket 9 therebetween, converging into a constricted neck portion. Thus the portions 6 provide yieldable or resilient supporting ledges for seating the side margins of the panel and with the terminals 8 spaced to abut the edges of the panels.

After these base members are secured in position upon the stud members, the panels are put in place with the margins of one face side seated upon the ledges of the base member, then means can be applied for holding the panels in position. This means may be in the form of a holding clip 10 attached to the studding by means of a nail or screw 11. Any number of these may be employed.

This holding strip may be of any desirable form but is preferably formed with an embossed portion 12 seating between the terminal portions 8 on the base member. On the other side of the embossment is a recess 13 in which the screw head may be received. The ends 14 extend from this embossed portion to project over the outer margin of the adjacent edges of two adjacent panels, thereby holding the panels securely in place upon the base member.

The panels having been secured in place, a finishing strip 15 of any desired shape may be used to cover the joint between adjacent panels. Means are preferably provided on the finishing strip to permit ready assembly and disassembly. The finishing strip may have one side plain and the other side provided with flanges 16 to abut against the faces of the panels.

At a midportion on the underside of the finishing strip, spring clips 17 may be attached by any suitable means 18 such as a rivet. This clip means is of light metal material with the sides 19 bent at an angle to a base portion 20 to conform substantially with the inclination of portions 8 on the base member, so that it may be sprung into the socket therebetween. Any number of these clips may be provided at spaced intervals on the finishing strip or the clip may be

a continuous piece. In either form, the finishing strip may be readily applied by merely pressing the spring clips so that they will be snapped or sprung into the socket between the terminal portions of the base member and may also be readily disengaged by pulling the clip member from the socket. This assembly unit permits the panels to be readily assembled and disassembled without the use of any permanent fastening means such as screw, nails or the like.

The holding clips 10 are preferably used in order to more permanently secure the panels in place, but if the finishing strips are alone desirable for holding the panels in place the holding strips may be dispensed with. Whether they or some other form of attachment be used, they are covered and concealed by the finishing strip which provides complete coverage for the joints.

While one embodiment has been described in detail for showing how the invention may be carried out, there may be various changes in details of construction without departing from the spirit of the invention.

I claim:

25 1. A panel fastening unit adapted to be mounted on a foundation member comprising a base member having ledge portions for seating the edges of a panel and means for spacing apart adjacent panels and providing yieldable walls 30 of a socket, a clip to hold the edges of the panel on the ledge portions of the base member, a finishing strip covering the space between the panels, and a clip attached to the finishing strip adapted to snap into the socket of the base member.

2. A panel fastening unit adapted to be mounted on a foundation member comprising a base member having flexible ledge portions for seating the edges of a panel and means for spacing 40 apart adjacent panels and providing yieldable walls of a socket, a clip to hold the edges of the panel on the ledge portions of the base member, a finishing strip covering the space between the panels, and a finishing strip provided with a 45 spring clip adapted to snap into the socket of the base member.

3. A panel fastening unit adapted to be mounted on a foundation member comprising a base member of flexible metal having retroverted 50 resilient ledge portions for seating the edges of a panel and terminal portions spaced apart to provide a socket, a clip to hold the edges of the panels on the ledge portions of the base member, and a finishing strip provided with means adapted to snap into the socket of the base member.

4. A panel fastening unit adapted to be mounted on a foundation member comprising a base member of flexible metal having retroverted 60 ledge portions for seating the edges of a panel and yieldable terminal portions disposed at an angle to the ledge portions to provide a socket,

a clip to hold the edges of the panel on the ledge portions of the base member, a finishing strip, and a clip attached to the finishing strip adapted to snap into the socket of the base member.

5. A panel fastening unit adapted to be mounted 5 on a foundation comprising a base member having yieldable ledge portions terminating in spaced apart angularly disposed terminals to provide a resilient socket and to separate the edges of adjacently laid panels, spaced apart 10 clip means spanning the socket and overlapping the edges of adjacent panels for holding same in position, and a finishing strip having a means adapted to snap into the socket.

6. A panel fastening unit adapted to be mounted 15 on a foundation comprising a base member having resilient ledge portions terminating in spaced apart angularly disposed terminals to provide a socket and separate the edges of adjacently laid panels, spaced apart 20 clip means spanning the socket and overlapping the edges of adjacent panels for holding same in position, and a finishing strip having a resilient means adapted to be sprung into the socket.

7. A panel fastening unit adapted to be mounted 25 on a foundation comprising a base member having yieldable ledge portions terminating in spaced angularly disposed terminals to provide a resilient socket and to separate the edges of adjacently laid panels, a holding clip adapted to bridge the spaced apart portions of the base member and be secured to the foundation for holding the adjacent edges of the panels against the edge portions, and a finishing strip having a 30 means adapted to snap into the socket.

8. A panel fastening unit adapted to be mounted 35 on a foundation comprising a base member having resilient ledge portions terminating in spaced apart angularly disposed terminals to provide a socket and separate the edges of adjacently laid panels, a holding clip adapted to bridge the spaced apart portions of the base member and be secured to the foundation for holding the adjacent edges of the panels against the ledge portions, and a finishing strip having a 40 resilient means adapted to be sprung into the socket.

9. A wall construction comprising a base member 45 disposed between spaced apart wall panels and provided with retroverted ledge portions spaced from the base member to resiliently support the wall panels, a fastening device provided in the base member between the ledge portions 50 for securing the base member in place, a holding clip for securing the wall panels upon the ledges of the base member, and a finishing strip attached to the base member for covering the holding clip.

CHARLES F. SPERRY.
